SOCKET FOR FLUORESCENT TUBES

Carl Edward Swanson, Chicago, Ill.

Application May 9, 1946, Serial No. 668,604

4-Claims. (Cl. 173—328)

1

My invention is directed to novel sockets for releasably retaining fluorescent tubes.

It is an object of my invention to provide sockets for fluorescent tubes having novel structural features including a pair of spaced apart adjacent secured plates or guards of non-conductive material, one of such plates being provided with holes for the reception and retention of the studs of a fluorescent tube and having between said plates a pair of elongated metal contacting strips or terminal members which are adapted to engage the ends of the tube contact studs, and which carries means for flexibly mounting the socket to a metal support, such as a reflector, hood, shield or the like.

A further object of my invention is the provision of novel sockets for fluorescent tubes which are yieldably and flexibly mounted with respect to the carrier element so that either one of a pair of opposed sockets may be manually flexed outwardly or away from the other of said sockets so as to insert and seat a tube into the sockets with the tube contact studs being yieldably engaged by metal contact members of said sockets respectively. A further object and accomplishment is the provision of sockets having the aforesaid characteristics and having suitably shielded spaced apart metal contact strips in each socket which normally will yieldably engage the respective ends of a fluorescent tube.

Other and further important objects and accomplishments of my invention will be apparent from the following description and appended claims.

On the drawings:

Fig. 1 is an enlarged elevation of one of my novel sockets looking at the inside face thereof.

Fig. 2 is a view looking at the edge side of the socket and showing a fragment of a tube in mounted position.

Fig. 3 is an elevation looking at the normally underside of a conventional reflector and showing one of various positions in which my novel sockets may be mounted.

Fig. 4 is an enlarged view looking at the rear end of one of my sockets.

Fig. 5 is an elevational view looking at another method of mounting two of said sockets in opposed relation in installations where the tube is to be mounted either vertically or at any other desired angle.

Fig. 6 is an enlarged side elevation of the spring or clip element shown in other views.

2

Fig. 7 is a side elevation of a modified embodiment of my invention.

Referring to Figs. 1 and 2, in which one embodiment of my invention is illustrated, the socket body is composed of two relatively flat plates or guards 10 and 11 formed of non-conductive material such as plastic or equivalent. Both said plates have oppositely extending wings, extensions or lugs 10—a and 11—a integral with the body portions thereof as shown in Fig. 1 so that shoulders are formed at the opposite edges of each side plates at the junctures of the narrower body portions and said extensions.

The normally inner plate 11 is provided with a pair of spaced apart holes 12 in its outer portion which are spaced to receive the end contact studs of standard types of fluorescent tubes.

The wider adjacent portions of said plates 10 and 11 are provided with a plurality of holes 15 (preferably three as indicated in Fig. 1) through which rivets 16 are passed and secured, the heads of the rivets being preferably on the outside face of plate 10.

A mounting member or connecting bracket 17 of relatively thin metal and having some flexibility and bent into rounded and angular cross section is secured by rivets 16 with one flat edge portion against the normally inside face of plate 10. The opposite edge or flange 17a is apertured and extends substantially perpendicularly to the plane of plate 10 and provides a convenient means of mounting the socket to a carrier 20 such as a reflector, hood, base or other element to which the sockets are to be mounted. The form of securance may vary, though in the drawings, I have shown a bolt 21 (Fig. 2). Such mounting will hold the outer plates 10 of a pair of mounting sockets in positions substantially perpendicular to the surface of the carrier element, designated in the illustration as 20. The carrier element 20, in the case of concavo-convex reflectors, hoods or caps are provided with suitably spaced slots (one thereof being designated as 23 in Fig. 2) of a size to permit insertion of the reduced ends of the sockets so that the shoulders of extensions 10a and 11a will act as stops and aid in rigid mounting.

Mounted and impinged between the plates 10 and 11 are a pair of spaced apart terminal strips or terminal contact members or strips 14 which extend from the projecting normally outer end of the plates to a point beyond holes 15, said contact strips being preferably slightly bent inwardly intermediate their ends as indicated in Figs. 2 and 6. Such bends in said contact mem-

bers 14 normally cause the outer reduced end portions to remain slightly spaced apart from plate 10, as indicated in Fig. 2, and thereby the outer portion of each of the contact strips 14 will normally press against the inner plate 11 so that a space is provided between such outer bent ends to permit flexing of each of said contact strips toward the inside surface of the outer plates 10 when the fluorescent tube is mounted. This provides space behind each of said contact members so that the distances between the outer ends thereof and the outer plate 10 may be varied when mounting the fluorescent tube and permitting a person to push the two contacting studs 24 of a tube 25 against the two contact members of one socket and thence manually flexing the other socket away from the first socket and snapping in the opposite two tube studs into the holes 12 of the second socket, whereupon the spring tendency of the contacting members 14 of both sockets will cause the outer parts of such members to contact and press against the ends of the two pairs of tube studs at both ends of a fluorescent tube.

In order to maintain the metal contact strips 14 in proper spaced apart position, both during assembly and in the finished product, I preferably form a boss 14-a in each of said contact members at a point between the mid-portion thereof and the terminal portions 14-b. The portions 14-b are preferably offset angularly as shown at 26 in Fig. 6, and such angularly bent portions are seated in two edge recesses 27 of the inner plate 11. The projecting portions of said contact members preferably have apertures 28 to facilitate connection of circuit wires which connect the sockets to a conventional source of power in the usual manner.

In Fig. 7 I have illustrated another embodiment of my invention wherein the non-conductive body of the socket is formed as a single piece, preferably by moulding a suitable plastic or equivalent non-conductive material in a form substantially the same as that hereinbefore described. Said non-conductive body 29 is formed with a pair of spaced apart longitudinally extending grooves, troughs, or recesses 30 which open to one side face of the body and in which are suitably mounted two of the contact members 14. One end of each of said contact members 14 are impinged and secured between the mounting bracket 17 and one end portion of said body 29 by means of a plurality of rivets 31 which extend through suitably spaced holes in said body 29 and in said bracket in the manner hereinbefore described.

In Fig. 7 I have shown the body 29 as provided with two pairs of optional integral lugs, bosses or extensions 32 which extend into each of the grooves 30 from opposite sides of each thereof and these are disposed above the bottom of grooves 30 so as to permit easy mounting of contact members 14 and retention thereof in inserted position.

The contact members 14 being bent outwardly at their free ends provide for flexing movement of the outer portions of said contact members 14 so that when two of said sockets are mounted to a carrier member such as a reflector, the tendency of said spring-like contacting members 14 to return to the normal position (after being pressed inwardly into the grooves in which they are disposed) will cause such free ends of said contact members or clips 14 to press against the

ends of the studs of a fluorescent tube mounted between a pair of such sockets.

In Fig. 5, I have illustrated a novel form of channeled carrier member or connecting bar 33 which has its ends curved and offset as shown and which ends terminate in integral end plates 34 which are parallel to each other. A pair of slots or openings (not shown) are formed in the offset ends of carrier bar 33 into which the sockets previously described may be inserted and secured as previously stated, as for example by screws 21. In installations where the fluorescent tube is to be mounted vertically, the lower end plate 34 is adapted to be secured to a base (for example a lamp base 35, only a fragment of which is shown in Fig. 5). The respective circuit wires, only parts of which are shown, are connected in the usual manner for fluorescent lamps, and those leading from the upper socket to the lower socket may be contained in the channel portion of carrier bar 33.

My invention provides a relatively inexpensive socket which has advantageous structural features which eliminate the need of rotating a fluorescent tube to properly mount it as is the case with presently known sockets, and which insures spring-pressed contact against the end studs of fluorescent tubes.

I am aware that various changes may be made in the embodiment of my invention herein specifically described without departing from or sacrificing any of the advantages of the invention or any features thereof, and nothing herein shall be construed as limitations upon the invention, its concept or structural embodiment as to the whole or any part thereof.

I claim:

1. In a socket for fluorescent tubes; a body composed of two substantially adjacent plates 40 of non-conductive material, one of said plates being apertured; a flexible metal mounting bracket of angular section; means securing said plates and said bracket together; and a pair of spaced elongated flexible metal contacting members between said plates and having portions thereof accessible through said apertures of one of said plates, said contacting members projecting beyond the rear edges of said plates to provide for electrically connecting same to a power source, said contacting members being bent, the pressure of the adjacent plates against said bent contacting members causing said members to be flexed.

2. In a socket for fluorescent tubes; a pair of 55 adjacent plates of non-conductive material, one of said plates having holes therein; a flexible metal mounting bracket of angular section; means securing said plates and said bracket together; and a pair of spaced apart metal flexible bent contacting members between said plates and having portions thereof accessible through said apertures of one of said plates, flexing of said contacting members into contact position occurring due to the pressure of said plates.

3. In a socket for fluorescent tubes, a body 60 of non-conductive material, said body having a pair of spaced-apart side openings therein adapted to receive the contact studs of a fluorescent tube; a metal attaching bracket having its opposite end portions disposed angularly with respect to each other; said bracket providing means of mounting said body upon a carrier member; and a pair of bent flexible spaced apart metal contact strips in said body having end portions thereof adjacent said openings of said

body, said contacting strips being connectable to a power source, said contacting strips being normally shielded by portions of said body, said body being flexibly mounted to permit transverse movement thereof with respect to a carrier on which the same is mounted, said contact strips being contactable because of the pressure of the component parts of said body on said contact strips.

4. In a socket for fluorescent tubes, a plurality of adjacent plates of non-conductive material having a space therebetween; one of said plates having a pair of spaced-apart openings therein; a pair of bent contacting strips mounted in the space between said plates and having parts thereof exposed adjacent said plate openings and a flexible metal bracket secured to one end portion of said plates, the pressure of said plates causing flexing of said strips into engagement with contact studs of a fluorescent tube; fastening elements securing said bracket and said

5 plates together, said bracket providing for transverse flexing of said plates so that when a pair of said sockets are mounted in opposed relation, either of said sockets may be flexed away from other socket to permit insertion of the contacting studs of a fluorescent tube therewith and into engagement with said contacting strips.

CARL EDWARD SWANSON.
